UNITED STATES PATENT OFFICE

FRANK LO CASTRO, OF BROOKLYN, NEW YORK, ASSIGNOR TO LA BELLE SPECIALTY CO., INC., A CORPORATION OF NEW YORK

DESIGN FOR A CLOCK FRAME FOR BANJO CLOCK

Application filed January 30, 1931. Serial No. 38,502. Term of patent 3½ years.

To all whom it may concern:

Be it known that I, FRANK LO CASTRO, a citizen of the United States of America, and a resident of Brooklyn, in the county of Kings and State of New York, have invented a new, original, and ornamental Design for a Clock Frame for Banjo Clock, of which the following is a specification, reference being had to the accompanying drawing, forming a part hereof.

In the drawings:

I claim:

The ornamental design for a clock frame for banjo clock, substantially as shown.

FRANK LO CASTRO.
